(57) CLAIM

The ornamental design for the power cutter body, as shown and described.

DESCRIPTION

FIG. 1 is a perspective view of a power cutter body of the present invention;

FIG. 2 is a front view of the power cutter body of FIG. 1;

FIG. 3 is a rear view of the power cutter body of FIG. 1;

FIG. 4 is a right side view of the power cutter body of FIG. 1;

FIG. 5 is a left side view of the power cutter body of FIG. 1;

FIG. 6 is a top view of the power cutter body of FIG. 1; and,

FIG. 7 is a bottom view of the power cutter body of FIG. 1.

Any broken lines in FIGS. 1-7 form no part of the claimed design.
